(57) **CLAIM**

The ornamental design for a flexible printed circuit board for battery module, as shown and described.

DESCRIPTION

FIG. 1 is a front perspective view of a flexible printed circuit board for battery module according to our design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

The flexible printed circuit board (FPCB) for a battery module of this design is made of metal and synthetic resin. The flexible printed circuit board (FPCB) for a battery module of this design is mainly used in an electric vehicle. Color forms no part of the claimed design.

1 Claim, 5 Drawing Sheets
